UNITED STATES PATENT OFFICE.

ERIK H. ALDEBORGH, OF POUGHKEEPSIE, NEW YORK, ASSIGNOR TO C. E. JOHANSSON, INC., OF POUGHKEEPSIE, NEW YORK, A CORPORATION OF DELAWARE.

SNAP GAUGE.

Application filed July 5, 1923. Serial No. 649,652.

To all whom it may concern:

Be it known that I, ERIK H. ALDEBORGH, a subject of the King of Sweden, and resident of Poughkeepsie, in the county of 5 Dutchess and State of New York, have invented a new and useful Improvement in Snap Gauges, of which the following is a specification.

In snap gauges of the type herein set forth 10 where inner and outer pairs of opposed adjustable anvils are employed, the desirability for both speed and accuracy in gaging the work is important. The spaces heretofore left between the opposed anvils of 15 the inner pair and the opposed anvils of the outer pair have not only been a deterrent to speed in the use of the gauge but also permitting the work being gaged to be scratched or otherwise marred by striking 20 the inner edges of the exposed ends of the anvils, which anvils as is well known, are of extremely hard steel.

The object of my invention is to provide means such as filler pieces bridging the 25 spaces between the anvils of the inner pair and the anvils of the outer pair, for facilitating the rapid gaging of the work without impairing the accuracy of the same, the work at the same time being guarded by 30 said filler pieces from being scratched or otherwise marred by the anvils.

Practical embodiments of my invention are represented in the accompanying drawings, in which

35 Fig. 1 represents a face view of a snap gauge of well known and approved construction, showing one form of filler piece.

Fig. 2 represents a section taken in the planes of the line II—II of Fig. 1.

40 Figs. 3 and 4 represent detail views showing a second form of filler piece in front and edge elevation in position for use.

Figs. 5 and 6 represent similar views of a third form of filler piece.

45 Figs. 7 and 8 represent similar views of a fourth form of filler piece.

Figs. 9 and 10 represent similar views of a fifth form of filler piece.

50 Figs. 11 and 12 represent similar views of a sixth form of filler piece.

The snap gauge 1 has its branches 2 and 3 provided with inner and outer pairs of opposed adjustable anvils 4, 5 and 6, 7 respectively, the exposed ends of said anvils 55 being beveled as is usual along their outer

edges to facilitate the admission of the work to be gaged.

The filler piece illustrated in Figs. 1 and 2 has a thicker intermediate portion 8 and thinner inner and outer end portions 9 and 10. The filler piece is split longitudinally as shown at 11 to form two branches having corresponding semi-circular recesses 12 and 13 for receiving the exposed end of one of the inner anvils. A screw 14 extends transversely through the branches of the filler piece at the thicker intermediate portion 8 for clamping the filler piece to the inner anvil 4 or 5, as the case may be. The outer end of the filler piece is provided with a 60 semi-circular recess 15 for receiving a portion of the outer anvil 6 or 7, as the case may be.

From the above description it will be seen that the filler piece is adjustable with the 65 inner anvil while the outer anvil is adjustable independently of the filler piece.

In the form shown in Figs. 3 and 4, the 70 filler piece 16 has no thicker intermediate portion but is of the same thickness throughout and the clamp screw 17 passes through the branches inside the inner anvil.

In the form shown in Figs. 5 and 6 the 75 filler piece 18 is of the same thickness throughout but the clamp screw 19 passes through the branches 20 and 21 between the inner and outer anvils, the filler piece in this instance being divided as shown at 22 from the outer semi-circular recess 23 to the 80 inner circular recess 24.

The form shown in Figs. 7 and 8 is quite 85 similar to the form shown in Figs. 5 and 6 except that the filler piece is provided with a thicker portion 25 intermediate the thinner inner and outer end portions 26, 27, 90 permitting the use of a larger screw than that shown in Figs. 3, 4 and 5, 6.

The form shown in Figs. 9 and 10 is quite 95 similar to the form shown in Figs. 3 and 4 except that the filler piece 28 is thicker at its inner end as shown at 29, to permit a larger clamp screw 30 to be used.

The form shown in Figs. 11 and 12 is one 100 adapted for anvils having enlarged heads. In this form the filler piece is completely divided into two half members 31, 32, connected by thin webs 33, 34, for embracing the inner anvil back of the head. Two clamp screws 35, 36 are shown for clamping the 105 half members of the filler pieces to the anvil.

In all of the forms herein shown and described, the filler pieces are substantially flush with the exposed ends of the outer anvils so that there is no danger of the work being marred when withdrawn from the gauge. Furthermore these filler pieces serve as guides for directing the work past the outer anvils to the inner anvils, thereby permitting a much more rapid manipulation of the gauge than heretofore.

In practice the surfaces of the filler pieces should be slightly below the gaging surfaces of the anvils for clearance. Under ordinary conditions the clearance should be from .002" to .005".

It is evident that various changes may be resorted to in the form, construction and arrangement of the several parts without departing from the spirit and scope of my invention; hence, I do not wish to be limited to the particular embodiments herein shown and described, but

What I claim is:—

1. In a snap gauge having outer and inner pairs of opposed anvils, of filler pieces bridging the spaces between the two pairs of anvils, the exposed ends of the outer anvils being substantially flush with the opposed faces of the filler pieces and the exposed ends of the inner anvils projecting beyond said faces.

2. In a snap gauge having outer and inner pairs of opposed anvils, of filler pieces bridging the spaces between the two pairs of anvils, the exposed ends of the outer anvils being substantially flush with the opposed faces of the filler pieces and the exposed ends of the inner anvils projecting beyond said faces, said filler pieces being carried by one pair of anvils.

3. In a snap gauge having outer and inner pairs of opposed anvils, of filler pieces bridging the spaces between the two pairs of anvils, the exposed ends of the outer anvils being substantially flush with the opposed faces of the filler pieces and the exposed ends of the inner anvils projecting beyond said faces, said filler pieces being

carried by one pair of anvils, and having recesses to permit them to more or less surround the other pair of anvils.

4. In a snap gauge having outer and inner pairs of opposed anvils, of filler pieces bridging the spaces between the two pairs of anvils, the exposed ends of the outer anvils being substantially flush with the opposed faces of the filler pieces and the exposed ends of the inner anvils projecting beyond said faces, said filler pieces being carried by the inner anvils.

5. In a snap gauge having outer and inner pairs of opposed anvils, of filler pieces bridging the spaces between the two pairs of anvils, the exposed ends of the outer anvils being substantially flush with the opposed faces of the filler pieces and the exposed ends of the inner anvils projecting beyond said faces, said filler pieces being carried by the inner anvils and having recesses to permit them to more or less surround the inner anvils.

6. In a snap gauge having outer and inner pairs of opposed anvils, of filler pieces bridging the spaces between the two pairs of anvils, the exposed ends of the outer anvils being substantially flush with the opposed faces of the filler pieces and the exposed ends of the inner anvils projecting beyond said faces, said filler pieces being clamped on the inner anvils.

7. In a snap gauge having outer and inner pairs of opposed anvils, of filler pieces bridging the spaces between the two pairs of anvils, the exposed ends of the outer anvils being substantially flush with the opposed faces of the filler pieces and the exposed ends of the inner anvils projecting beyond said faces, said filler pieces being clamped on the inner anvils and having recesses to permit them to more or less surround the outer anvils.

In testimony, that I claim the foregoing as my invention, I have signed my name this 15th day of May, 1923.

ERIK H. ALDEBORGH.
